UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

PILE-ELEVATING MECHANISM.

Application filed July 12, 1921, Serial No. 434,078. Renewed May 12, 1925.

This invention relates to pile elevating mechanisms for sheet feeding machines and has for its object to provide improved means for locating a pile of sheets with respect to the sheet feeding mechanism, for governing the upward movement of the pile raising table, and whereby the motor energizing circuit may be automatically broken to prevent an overfeed of the pile or table. Subsidiary objects of invention will appear in the specification and be pointed out in the appended claims, reference being had to the accompanying drawings which exemplify my invention in a preferred embodiment and in which—

Figure 1 is a transverse vertical section of a sheet feeding machine provided with my improvements, said section corresponding to the line 1—1, of Figure 2;

Figure 2 is a side elevation of the same;

Figure 3 is a top plan view of the pile holding table according to line 3—3, of Figure 1, parts being broken away and parts shown in section;

Figure 4 is a side elevation on an enlarged scale of the governor for the pile elevating mechanism, parts being broken away and parts shown in section; and

Figure 5 is a similar side elevation showing the parts of the governor in changed positions.

Figure 6 is a perspective view of the table-elevating mechanism showing the complete operating connections between the several parts.

In the embodiment of my invention shown on the drawings, the floor sockets 1 serve to mount the standards 2 which are rigidly connected above by side bars 3 and side frames 4. Depending from the side bars 3 are oppositely arranged hangers 5, 5 for journalling laterally spaced shafts 6, 6. Each of said shafts 6, 6 is provided at its forward end with a skew gear 7 which meshes with a worm 8. The worms 8 are keyed to opposite ends of a drive shaft 9 which extends across the front of the machine. This shaft 9 is driven in a manner to be hereinafter pointed out. Each of the shafts 6 is provided with suitable sprockets (not shown) within suitable housings 10, 10. Suitable means for raising the pile supporting means to be hereinafter referred to are provided as follows. Sprocket chains 11 which pass around said sprockets and thru

the housings 10, 10 are provided with releasable shackles 12 which may be detachably connected to the lateral bars 13. Referring now to Figure 2, in the preferred embodiment of my invention, suitable means for supporting a pile of sheets P, include a table 14 movably mounted on spaced transverse beams 15, 15. For this purpose, a plurality of rollers 16 are arranged in series along the upper edge of each of the supporting beams 15, 15. The pile carrying table 14 rests upon these rollers. The beams 15 are provided on their adjacent bases with castings 17, 17 arranged near opposite ends of the cross-beams 15, 15. Each of these castings 17 is provided with a plurality of socket bearings 18 for mounting the opposite ends of a table adjusting shaft 19 which carries an eccentric cam disk 20 provided with sockets 21 for the introduction of a suitable bar or lever for oscillating the cam 20 which bears against the lateral edge of the table 14 and thereby serves to position said table for the purpose of centering the pile of sheets carried thereby. In order to provide the pile supporting means with suitable suspension members the opposite ends of each of the cross-beams 15, 15 are provided with triangular housings 22, 22. Presented outwardly from each of the housings 22, 22 is a hook 23, between which and the upper outside edge of the housing 22 extends a cam surface 24.

It will be understood from an inspection of Figure 1 that whenever the side bars 13 which are suspended from the active ends of the chains 11, are permitted to move downwardly, they will be displaced outwardly by the cam surfaces 24, 24 as they slide over the hooks 23, 23 when the beams 15, 15 are in their initial positions of rest indicated in dotted lines in Figure 2. When, however, the direction of movement of said chains is reversed, said side bars 13, 13 are raised into engagement with the suspension members or hooks 23, 23. Suitable pads or supports 25, 25 are connected to the floor in suitable positions to carry these cross-beams before the load is superimposed upon the table 14 after said table has been placed in position on said beams. Referring now to Figure 3, each of the forward standards 2, 2 is provided with a bearing boss 26, 26 within which is mounted a stay shaft 27.

Presented rearwardly from each of the bearing bosses 26 is a bracket arm 28 within which is mounted a cross-rod 29. Secured to the cross-rod 29 are a plurality of front edge guides 30, 30 which are adapted to slidably engage the front edge of the pile as the feed table is raised. Adjacent the outer ends of the rod 29 and extending upwardly therefrom are laterally spaced track bars 31, along which rollers 32 are adapted to travel, said rollers being journaled on laterally projecting pins 33, carried by the suspended side bars 13, 13. Adjacent the lower end of each of the track bars 31 as shown best in Figure 2, a wedge shaped block 34 is mounted in suitable position to displace the cam roller 32 in such a way as to hold the forward edge of the feed table 14 away from the vertical guides 30, 30.

10 The importance of this construction will be seen. After a feed table 14 has been arranged as shown in dotted lines in Figure 2, a pile of sheets may be arranged thereon in exact alinement with the front edge 15 of the feed table, or to slightly overhang the same. Shortly after the feed table 14 begins its upward movement, the cam rollers 32, 32 will pass off from the cam blocks 34, 34 when the pile P will be free to swing into engagement with the guides 30, 30. For 20 this purpose, the points of suspension of the side bars 13, 13 are selected with respect to the positions of the chain sprockets so as to impart a tendency to the side bars 13, 13 25 to swing forwardly. In this way, the front edge of the pile is retained in close relation to the guides 30, 30.

Referring now to Figures 1, 2, 4 and 5, it will be seen that the drive shaft 9 which 30 is common to the table elevating shafts 6, 6 being connected to said shafts by skew gears 7, 7 and worms 8, 8 at either end of shaft 9 is provided with a ratchet 35. As shown best in Figures 4 and 5, the ratchet 35 may be rotated step by step by means of a pawl 36 which is pivotally mounted on a pin 37 which projects laterally from an arm or block 38 which oscillates freely upon the shaft 9. The forward end of a spring rod 39 is also pivotally connected to the pin 37 and carries a collar 40 between which and a spring rod eye-bolt (not shown) is interposed a compression spring 41 which tends to move the arm 38 in a clockwise direction. 45 The arm 38 carries a pin or stud 42 to which is pivoted the rear end of a connecting rod 43, said connecting rod being provided with an elongated slot 44 in the opposite end thereof to accommodate a laterally projecting pin 45 carried by a rotor cam plate 46 which is keyed to a cam shaft 47. Pivotally mounted at 48 on the upper side frame is a 50 detent or dog 49 which is normally adapted by gravity to rest on a curved surface 50 on the oscillatory arm 38 and to abut against

a shoulder 51 for preventing the spring 41 from throwing said arm 38 toward the right. In this position of the parts, the pin 45 travels to and fro along the slot 44 without rotating the shaft 9. The length of slot 70 44, however, is such that during the periods in which the pin 45 is adjacent its extreme left-hand position, said pin operates to relieve the pressure which is exerted by the spring 41 against the dog or detent 49 75 through the arm 38. At these times said dog or detent is left free to be raised out of the path of shoulder 51 by a governor mechanism which comprises the following parts. 80

As shown in Figure 1, a center bracket 52 is provided with a lug 53 upon which is pivoted a lever 54 provided at its lower end with a roller 55 adapted to rest upon the top of a pile of sheets and to gauge the elevation thereof. The other arm of said lever 54 is pivotally connected at 56 with a connecting rod 57, the upper end of said connecting rod being pivotally connected to an arm 58 which is keyed to a rock shaft 59. 90 As shown in Figures 4 and 5, a second crank arm 60 is keyed to the rock shaft 59. Said crank arm 60 is pivotally connected at 61 to a link 62 which depends therefrom and is provided at its lower end with a slot 63 within which operates a pin 64 carried by the dog 49. It will be understood that when the height of the pile becomes sufficiently reduced, the roller 55 in its downward movement serves to elevate the connecting rod 57 100 together with the crank arms 58 and 60, the link 62 being raised and the dog 49 being lifted to release the arm 38 after the pin 45 has counteracted the pressure of spring 41. When the arm 38 is thus released, it will 105 be moved toward the right with connecting rod 43 by the action of spring 41 and under the constraint of pin 45 in slot 44. When by the continued rotation of the cam 46 the pin engages the left-hand extremity of slot 110 44, pawl 36 will rotate the ratchet 35 and shaft 9 in counter-clockwise direction to elevate the pile. The dog 49 is held out of engagement with the shoulder 51 until operation of the pawl 36 has raised the pile 115 sufficiently to permit the dog 49 to again drop into its locking position.

It will be seen from Figure 4 that the cam plate 46 has an outer run which operates on a cam roller 65 in the forward end of a cam arm 66 which is keyed to the rock shaft 59 for raising the roller 55 from the pile while the sheet is being forwarded. Said cam roller 65, during the period in which power is being imparted to the arm 38 for rotating the shaft 9, traverses the low portion 67 of the cam plate 46. 120

Pivotally connected at 68 to the cam arm 66 is the upper end of a connecting rod 69. As shown best in Figure 1, the lower end of 125

3 said connecting rod is pivotally connected at 70 with a crank arm 71 which is keyed to an oscillatory shaft 72 mounted on pedestals 73 which extend upwardly from a 5 frame or support 74 which is mounted on one of the forward standards 2. The shaft 72 also carries a depending lever arm 75 which is adapted under certain conditions to throw a hand operated knife switch 76 10 into circuit breaking position. Said knife switch is mounted on a controller board 77 which carries a suitable resistance box 78 for controlling the starting and stopping of the motor by hand. It will be understood 15 that said motor constitutes means independent of the rotor 46 for elevating the sheet support. By an inspection of Figure 5 it will be seen that if the feed table has been set into motion, there will be an upper limit 20 beyond which the top of the pile is not permitted to pass. Thus when the pile reaches the position shown in Figure 5, the connecting rod has been moved upwardly to a sufficient degree to cause the lever arm 75 25 to displace the switch 76, thus stopping the motor, this being effected thru the upward movement of the governor lever 54 which, thru the connection described, operates to elevate the lever 66 to the position shown in 30 Figure 5.

Referring now to Figure 6, the armature shaft 79 of a motor 80 carries a sprocket wheel 81 around which passes a sprocket chain 82, said chain also passing around a 35 sprocket wheel 83 on shaft 84 which latter is mounted in suitable bearings. Shaft 84 carries a gear 85 from which is driven shaft 86 through gears 87 and 88. Gear 87 is always in mesh with a gear 89 journaled 40 on a stud 89' carried by the frame. Gear 89 meshes with a gear 90 keyed on shaft 86. Gear 88 is always in mesh with gear 87, but never in mesh with gear 89. Gears 87 and 88 are mounted on a swing 45 arm 90' that is freely swung on the stud 89'. This arm 90' can be moved to mesh the gear 87 with gear 85 by moving said arm to the right (as seen in Fig. 6) or to mesh gear 88 with gear 85 by moving said arm to the 50 left or to neutral position in which neither gear 87 nor 88 is in mesh with 85. The arm 90' is held in any adjusted position by means of a lock screw 91 engaging one of a series of countersunk recesses in arm 90' indicated 55 at 92, 92^a and 92^b, and connected by an elongated slot 93.

Shaft 86 carries a gear 93' and a hand-wheel 94, the former meshing with a gear 95 keyed to the shaft 9. When the gear 60 87 is meshed with 85, shaft 86 is rotated from shaft 84 through gears 85, 87, 89 and 90 to lower the table. When the gear 88 is meshed with 85, shaft 86 is rotated from shaft 84 through gears 85, 88, 87, 89 and 90 to raise the table.

To disengage the dog 36, the arm 90' is provided with a projection 96, the free end of which is connected to the lower end of a member 97 provided with a cam slot 98. A pin 99 carried by an arm 100 engages 70 in said slot. Said arm is mounted on a shaft 101 that has pinned thereto a cam arm 102. A roller 103 mounted on the side of dog 36 engages the cam arm. Accordingly, when the swing arm 90 is moved either to the 75 right or to the left the cam arm 102 will act through the connections described, to elevate the dog 36 out of engagement with the ratchet 35.

I claim:

1. In a sheet feeding machine, pile supporting means, means for raising said pile supporting means, means for guiding the front edge of a pile of sheets mounted on said pile supporting means, and means for holding said pile supporting means away from said front edge guiding means during the initial movements of the former and permitting a closer approach to said guiding means after a predetermined initial movement.

2. In a sheet feeding machine, pile supporting means, means for raising said pile supporting means, means for guiding the front edge of a pile of sheets mounted on said pile supporting means, and means for holding said pile supporting means away from said front edge guiding means during the initial movements of the former and permitting a closer approach to said guiding means after a predetermined initial movement, said holding means comprising interengaging parts of which one is carried by said pile supporting means and the other is connected to said front edge guiding means.

3. In a sheet feeding machine, pile supporting means, means for raising said pile supporting means, means for guiding the front edge of a pile of sheets mounted on said pile supporting means, and means for holding said pile supporting means away from said front edge guiding means during the initial movements of the former and permitting a closer approach to said guiding means after a predetermined initial movement, said holding means including a cam roller journaled on said pile supporting means and a cam block arranged to engage said cam roller during the lowermost reaches of said pile supporting means.

4. In a sheet feeding machine, pile supporting means, means for raising said pile supporting means, means for guiding the front edge of a pile of sheets mounted on said pile supporting means, and means comprising interengaging parts for holding said pile supporting means away from said front edge guiding means during the initial movements of the former and permitting a closer

approach to said guiding means after a predetermined initial movement, one of said interengaging parts being movable relatively to the other by the movement of said pile supporting means.

5. In a sheet feeding machine, a pile holding table, supporting beams for said pile holding table, said beams being provided at opposite ends with downwardly presented hooks and outwardly presented cam surfaces, side bars movable downwardly and displaceable outwardly by said cam surfaces and upwardly to come into engagement with said hooks for lifting the table and means movable alternately in opposite directions for lowering and raising said side bars.

6. In a sheet feeding machine, a plurality of pile supporting means, and means movable alternately in opposite directions for raising one of said pile supporting means after the other, each of said pile supporting means being provided with suspension members disposed in the path of said raising means and adapted to displace said raising means on its downward movement and to intercept said raising means on its upward movement so as to be raised thereby.

7. In a sheet feeding machine, the combination with pile supporting means, of sprocket chains for suspending said pile supporting means, said pile supporting means being provided with downwardly presented hooks provided with upwardly presented cam surfaces intersecting the planes of movements of the suspension ends of said sprocket chains, and means carried by the suspension ends of said sprocket chains for slidably engaging said cam surfaces to be laterally displaced on the downward movement of said suspension ends of the sprocket chains and for engaging said downwardly presented hooks when said suspension ends of the sprocket chains are raised.

8. In a sheet feeding machine, a pile holding table, beams for supporting said table, sockets carried by said beams, a shaft adapted to be carried by said sockets, and an eccentric carried by said shaft and bearing against said table and adapted to rotate to move said table.

9. In a sheet feeding machine, a pile holding table, a motor, driving connections between said motor and pile holding table for raising the latter, means adapted to be displaced by the upward movement of a pile of sheets on said table for rendering inoperative the driving connections between said motor and the pile holding table, and means automatically disconnecting said motor and driving means.

10. In a sheet feeding machine, beams for carrying a pile holding table, each of said beams being provided with housings at opposite ends thereof, said housings being provided with outwardly presented hooks, sepa-

rate side bars for engaging said hooks, and means for suspending and raising said side bars, said beam end housings being provided with cam surfaces for guiding said side bars outwardly as they are lowered past said beams.

11. In a sheet feeding machine, beams for carrying a pile holding table, each of said beams being provided with housings at opposite ends thereof, said housings being provided with outwardly presented hooks, separate side bars for engaging said hooks, and means for suspending and raising said side bars, said beam end housings being provided with cam surfaces for guiding said side bars outwardly as they are lowered past said beams, said suspension means being provided with shackles for releasably connecting said side bars.

12. In a sheet feeding machine, beams for carrying a pile holding table, each of said beams being provided with housings at opposite ends thereof, said housings being provided with outwardly presented hooks, separate side bars for engaging said hooks, and means for suspending and raising said side bars, said beam end housings being provided with cam surfaces for guiding said side bars outwardly as they are lowered past said beams, said suspension means being provided with shackles for releasably connecting up said side bars, said side bars being provided with cam rollers thereon, front edge guides for a pile of sheets mounted on said table, and cam blocks cooperating with said cam rollers for holding the front edge of said pile away from said guides during the initial upward movements of said side bars.

13. In a sheet feeding machine, pile elevating means, a pile elevating governor for controlling the elevation of said pile elevating means, a motor controlling switch and means operably connecting said governor and said switch, said connecting means including a cam operated lever for controlling the operation of said governor, a lever for throwing said switch, and means for connecting said cam and switch throwing levers.

14. In a sheet-feeding machine, pile supporting means, means for raising said pile supporting means, means for guiding the front edge of a pile of sheets mounted on said pile supporting means, and means for holding said pile supporting means away from said front edge guiding means during an initial movement of said pile supporting means and permitting a closer approach to said guiding means after said initial movement is completed, said holding means including a stationary part and a movable part movably engaging said stationary part.

15. In a sheet-feeding machine, pile supporting means, means for raising said pile supporting means, means for guiding the

front edge of a pile of sheets mounted on said pile supporting means, and means for holding said pile-supporting means away from said front edge guiding means during an initial movement of said pile supporting means and permitting a closer approach to said guiding means after said initial movement is completed, said holding means including relatively movable parts in engagement with each other during said initial movement.

16. In combination, a pile elevating shaft, a ratchet keyed thereto, an arm loosely mounted on said shaft, a pawl carried by said arm and adapted to engage said ratchet to rotate said shaft, a pivoted dog engaging said arm to normally hold the same stationary, a governor lever and connections between said lever and dog for disengaging the latter from said arm including a link having a pin and slot engagement with said dog, and means for rotating said shaft through said pawl when said dog is so disengaged.

17. In combination, a pile elevating shaft, an arm loosely mounted thereon, a step-by-step connection between said arm and said shaft, a pivoted dog engaging said arm to normally hold the same stationary, a governor lever and connections between said lever and dog for disengaging the latter from said arm including a cam actuated member, a link connecting said member and lever, a link connecting said member and dog, and means for rotating said shaft through said step-by-step connection when said dog is so disengaged.

18. In combination, a pile holding table, a motor, a pile elevating shaft, connections between said motor and said shaft, a governor lever, a cam operated lever, connections between said governor lever and said cam lever, and connections between said cam lever and said motor.

19. In combination, a pile holding table, a motor, a pile elevating shaft, connections between said motor and said shaft, a governor lever, a cam operated lever, connections between said governor lever and said cam lever and connections between said cam lever and said motor, means carried by said shaft for rotating the same, a dog normally holding said means out of operative engagement with said shaft, and connections between said cam lever and said dog.

20. In a device of the character described, the combination of a sheet support, a governor lever engaging the top of the pile of sheets and operating to normally maintain the top of the pile at a predetermined

height, a power shaft, connections between said shaft and support, shaft-rotating means, a dog normally preventing the operation of said means, and connections between said governor lever and dog including a pivoted lever and a link, independent power means, means controlling said independent means from said lever, and a pin and slot connection between said link and dog.

21. In a device of the character described, the combination of a sheet support, governing means engaging the top of the pile of sheets and normally maintaining the same at a predetermined height, means for automatically elevating said support, a device for normally preventing operation of said support elevating means, an independent source of power, lost-motion connections between said governing means and said device, and connections between said governing means and said independent source of power to cut off the latter when said governing means is elevated beyond a predetermined height by said independent source of power.

22. In a device of the character described, the combination of a sheet support, a source of power from which the pile is normally maintained at a predetermined height, independent power means for elevating the pile, and a combined governor and safety lever normally operating to maintain the pile at a predetermined height from said source of power and to disconnect said independent means when said pile is raised thereby above a predetermined height.

23. In a device of the character described, the combination of a sheet support, governing means normally maintaining the pile at a predetermined height, independent means for elevating said support, and connections between said governing means and said independent means for automatically disconnecting said independent means when said pile is elevated thereby beyond a predetermined height.

24. In a device of the character described, the combination of a sheet support, a source of power for elevating said sheet support, governing means normally maintaining the pile at a predetermined height from said source of power, independent power means for elevating said support, and connections between said governing means and said independent means for automatically disconnecting said independent means when said pile is elevated thereby beyond a predetermined height.

CARL E. CHRISTOPHEL.
